UNITED STATES PATENT OFFICE.

AARON E. ROSENTHAL, OF CHICAGO, ILLINOIS, ASSIGNOR TO BEACON STEEL FURNITURE CO., OF CHICAGO, ILLINOIS, A CORPORATION OF ILLINOIS.

REMOVABLE FOOT FOR A SUPPORTING LEG.

Application filed January 27, 1927 Serial No. 163,993.

My invention relates to a removable foot for a supporting leg, and more particularly to such a foot for the leg of a chair or similar piece of furniture which is provided 5 with a lower hollow portion.

The main object of the invention is to provide a foot which is made up of parts that are easily constructed and readily assembled, and even disassembled if desired, and are 10 made of good durable material, especially the floor-engaging part of pliable and anti-slipping material; and include a resilient stem or shank portion with a curved part which will hold the foot firmly in the hollow 15 leg and yet permit ready removal therefrom; thus providing a foot which is economical in manufacture, conveniently applied, and is durable and efficient in use.

Other objects and advantages are attained 20 with my invention, as will become apparent from the following description, taken in connection with the accompanying drawing disclosing the preferred form of my invention, and in which,

25 Fig. 1 is a side view of a chair with my improved foot mounted in position on the leg thereof;

Fig. 2 is an enlarged view, partly broken away, showing the lower part of the chair 30 leg with the foot mounted thereon;

Fig. 3 is a view of the strap or blank from which the resilient shank is formed;

Fig. 4 shows in perspective the parts of 35 the foot disassembled;

Fig. 5 is a side view of the foot; and Figs. 6 and 7 are vertical and horizontal 40 sections on lines 6—6 and 7—7 of Fig. 2, respectively.

In the drawing I have shown the preferred 45 form of construction embodying my invention, and this comprises a cap 12, preferably of metal, with a slot or opening 13 in its top, and a block 14 of pliable or compressible and non-abrasive material, which 50 will not injure the polished floors and will not slip thereon, and will provide a slight amount of pliability and resiliency to the chair leg, thus making the chair comfortable and steady for the user. This block 14 has 55 a top or head part 15 which is clamped and held in the inturned edge 16 of the cap to retain it firmly in position therein.

The foot also comprises a shank or stem 60 which is formed and consists of a blank or strap of resilient metal, as best shown in Fig.

3, bent and doubled over at its middle forming a flattened part 17 and having toe parts or means 18 at the ends, as best shown in Fig. 4. Arms 19 extend up from said parts, through slot 13, being slightly spaced and 60 having their upper ends 20 curved and brought together, preferably in the shape of a bulging or substantially oval portion, thus providing a flat and resilient shank or stem part. 65

This flat and resilient shank part is especially arranged and adapted to fit in the flat, hollow lower part 21 of the leg 22 of a chair or other piece of furniture, and the metal or material of said leg is preferably 70 dented or pressed inwardly, beneath said curved or bulging part 20, as at 23, see Figs. 6 and 7, to firmly but removably retain said foot in position in the leg.

It is apparent from the above disclosure 75 that I have provided an improved foot in which the parts are readily constructed and assembled and firmly held together, and may be disassembled and the block 14 replaced, if desired, by slightly loosening the inturned 80 edge 16 at one side of said block; and it is also apparent that this construction of resilient shank will hold the foot firmly in position in my hollow chair leg, with or without the use of the dented part 23 on the 85 leg, and will also permit ready and convenient mounting and removing of this foot on the leg.

What I claim as my invention and desire 90 to secure by Letters Patent is:

1. A foot for a supporting leg, comprising a cap with an opening, a block of pliable material mounted in said cap, and a shank extending through said opening and having a doubled over portion with a flat 95 toe part mounted in said cap and an upper oval resilient part for mounting it in the leg to permit convenient withdrawal therefrom.

2. A foot for a hollow supporting leg, comprising a cap with a slot in its top, a block of pliable material mounted in said cap, and a shank consisting of a strap of resilient metal having a doubled and flattened portion adjacent its middle and provided with 100 toe means mounted within said cap, said shank having flat arms spaced and extending removably through said slot and being curved at the top for removably mounting 105 said foot in the hollow leg. 110

3. A foot for a hollow supporting leg, comprising a cap with a slot in its top, a block of pliable material having a head clamped in the inturned edges of said cap, and a shank consisting of a strap of resilient material having toe means and a bent over portion at its middle which is mounted in said cap over said head, said shank having spaced arms extending from said bent-over part through said slot and forming a bulging part at the top for resiliently and removably mounting it in the leg.

10 4. In combination with a leg having a flat

hollow portion, a foot comprising a cap with a slot in its top, a block of pliable material mounted in said cap, and a shank having a toe part mounted in said cap and resilient arms forming a flat part extending through said slot and terminating in curved ends mounted in said hollow portion, the material of said leg being dented beneath said curved ends for firmly but removably retaining said foot in position in said leg.

15 20 In testimony whereof I have signed my name to this specification.

AARON E. ROSENTHAL.
